HIRAM CHAMBERLAIN, OF CALAIS, MAINE.

Letters Patent No. 69,073, dated September 24, 1867.

IMPROVED MACHINE FOR CHOPPING MEAT.

The Schedule referred to in these Letters Patent and making part of the same.

TO ALL PERSONS TO WHOM THESE PRESENTS SHALL COME:

Be it known that I, HIRAM CHAMBERLAIN, of Calais, in the county of Washington, and State of Maine, have invented a new and useful Machine for Slicing and Mincing or Chopping Meat, or other matters; and I do hereby declare the same to be fully described in the following specification, and represented in the accompanying drawings, of which—

Figure 1 is a top view,

Figures 2 and 3 are vertical and transverse sections, and

Figure 4 an elevation of it.

In such drawings A denotes the frame of the machine. A driving-shaft, B, suitably supported in bearings, upheld by the said frame, and provided with a crank, *a*, carries a spur-gear, *b*, which engages with a pinion, *c*, fixed on another shaft, *d*. The said shaft *d* is arranged over the driving-shaft, has a bell-crank, *e*, and carries a slicing-wheel or disk, *f*. This wheel is shown in side view in Figure 5, and in section in Figure 6. It has three or any other suitable number of throats *g g g* extending through it, there being a cutting-knife, *h*, like a plane-iron fixed in each of the throats, and so as to stand at an acute angle with the face or side of the wheel. Besides these knives, the wheel has a series of cutters or cross-cut knives, *i i i*, projecting from its face, and in advance of each knife *h*. The knives *i i i* are to pass down through the meat, preparatory to each slice being taken therefrom by each of the slicing-knives *h h h*. Thus it will be seen that by the conjoint operations of the slicing and cross-cut knives slices will be cut from the meat, and such meat will be so cut into that each of the slices will be separated into several parts, all of which will pass through the throats of the wheel and into the wheel-case C. The said case C surrounds the wheel and extends down to and opens through a platform, D, arranged over the rotary mincing-tub E. A hopper, F, formed as shown in vertical section in Figure 7, and in front view as exhibited in Figure 8, is so applied to the frame A and the case C as to discharge into the said case, and against the face of the wheel therein, any meat placed in such hopper. An adjustable shoe, *k*, is applied to the lower part of the hopper, and held thereto by a screw, *l*, and a nut, *m*, the screw passing through a slot in the inclined side or chute *n* of the hopper. The shoe is provided with lips *o o* which project upward from its edges and against the opposite sides of the hopper. The purpose of the shoe is to support the meat while it may be in the act of being cut by the knives of the wheel, and such shoe is adjustable in order that it may be moved up as nearly to them as possible, and especially in any case of wearing or cutting away of its lower edge. The case C I construct in two separate parts, that is to say it is divided into two sections *p p* by a plane going through it transversely and through the axis of the cutting-wheel; the same being to enable each part *p* to be readily removed from the wheel for the purpose of being cleansed, as occasion may require. These parts are supported by small studs *q q* projecting from them and resting on a cross-rail, *r*, of the frame A, against which the said case C abuts, it being kept up to the rail by an arched bar, *s*, whose ends are inserted in mortises or sockets *t t* made in the frame A. The mincing-tub E simply rests on the upper side of a horizontal worm-gear, *t¹*, a pivot, *t²*, from which extends into a hole, *u*, in a slide, *u*, placed between and against two parallel and dove-tailed guides *v v* fixed on the base *w* of the frame A. By means of the slide *u* and its guides *v v* the tub may be withdrawn from the wheel-case, or arranged in place underneath it, as circumstances may require, whether for discharging the minced meat from the tub, or for cleansing the said tub. Small studs *x* project horizontally from the periphery of the mincing-tub. Other studs extend vertically from the upper surface of the gear *t¹*. Each of the studs *x*, by contact with one of the studs *y*, causes the tub to revolve with the gear, when the latter is in revolution. A worm or screw, *z*, fixed on a shaft, G, engages with the teeth of the worm-gear *t¹*. An endless belt, H, running on a pulley, I, fixed on the driving-shaft, and another pulley, K, fixed on the shaft G, serve to transmit rotary motion to the said shaft G, when the driving-shaft is in the act of being revolved by manual power applied to its crank.

The meat, after having been sliced and reduced in manner as stated, will be discharged into the mincing-tub. A knife, *i*, (arranged so as to play up and down within the said tub, and so moved by means of the bell-crank *e*, a connecting-rod, *K'*, and a pitman or shank, *L*, arranged as represented,) will mince or chop the meat while the tub may be in revolution.

In such machine I claim the following, that is to say—

I claim the combination as well as the arrangement of the slicing, and mincing or chopping mechanisms, substantially as specified, the slicing mechanism consisting of the rotary wheel with its slicing and cross-cut knives, the hopper and the wheel-case, and the means of revolving the wheel, and the mincing mechanism, consisting of the rotary mincing-tub, its reciprocating knife, and mechanism for operating the two, as specified.

I also claim the combination of the adjustable shoe K, with the hopper and the slicing-wheel provided with the slicing and cross-cut knives, as described.

I also claim the combination and arrangement of the studs q, and the retainer or arched bars with the frame A, and the slicing-wheel case C, made in two parts and applied to the slicing-wheel, as specified.

I also claim the combination and arrangement of the slider u and its guides v with the mincing mechanism, when connected with a slicing mechanism, and so as to operate therewith, as set forth.

HIRAM CHAMBERLAIN.
